REGISTER MECHANISM

Filed Aug. 26, 1927

UNITED STATES PATENT OFFICE.

WILLIAM W. CROW, OF TREECE, KANSAS.

REGISTER MECHANISM.

Application filed August 26, 1927. Serial No. 215,665.

The present invention relates to registers, and aims to provide a novel and improved mechanism for registering the operations of a mine hoist or the like.

5 A further object of the invention is the provision of a registering mechanism of the kind indicated which has novel provisions for preventing false operation thereof, so as to assure of accurate registrations of the operations of the hoist.

10 A still further object is the provision of a novel device or circuit controller for operating or controlling a register and adapted to be operated automatically by the hoist bucket

15 when same is dumped.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a diagrammatical view of the hoist and registering apparatus.

Fig. 2 is an elevation of the register.

A hoist is illustrated diagrammatically, 20 consisting of a hoist bucket 7 suspended by a cable 8 which passes over a pulley 9, for lifting material from a mine, or the like, and the bottom of the bucket 7 has an eye 10 or other element for the engagement of a hook 11 on the end of a dumping cable or rope 12, so that when the bucket 7 is elevated out of the mine the hook 11 may be engaged with the eye 10, and when the cable 8 is slackened the bucket will be suspended upside down, as seen in 35 dot and dash lines in Fig. 1, for dumping the bucket at one side of the mine shaft.

In carrying out the invention there is provided a register 13, which may be located in the office or at any other suitable distant point, in order that the operations of the hoist may be conveniently noted, and said register 13 is controlled by a switch device or circuit controller 14, with an electrical circuit 15 connecting said device and register.

50 The switch device 14 includes a substantially horizontal lever 16 fulcrumed to a post 17 secured on a beam 18 supported by or forming part of the framework of the hoist, and the upward movement of the lever 16 is limited by a stop 19 in which the lever works, said stop being secured to the beam 18. A

spring 20 is confined between the lever 16 and beam 18 for raising the lever. A bridle or suspension bar 21 is pivotally connected with the lever 16, and the dump cable 12 is connected to said bar 21. The lever 16 has a longitudinal series of staples or eyes 22 for the connection of the bar 21, for purpose of adjustment, to regulate the weight that is required to depress the lever 16 against the pressure of the spring 20. The bar 21 may thus be adjusted on the lever 16 according to the weight of the bucket 7 and its contents, so that a predetermined weight is required before the lever 16 is depressed.

70 The depression of the lever 16 closes the circuit 15 to operate the register 13, and for this purpose the circuit 15 includes a pair of co-operable contacts 23 and 24, the contact 24 being carried by a leaf spring or arm 25 carried by the lever 16 so that when the lever 16 is depressed the contact 24 is raised into engagement with the contact 23 providing such engagement of the contacts is otherwise permitted. The contact 23 is carried by an arm 26 which is hinged, as at 27, to a support or case 28, and a spring 29 is connected to said arm 26 to swing same downwardly, the downward movement of said arm being limited by an adjusting screw 30 carried thereby which seats on a stop 31. The arm 26 is thus permitted to swing upwardly when the contact 24 is raised, the arms 25 and 26 both being capable of yielding.

85 In order to prevent the circuit 15 from being closed by the depression of the lever 16, excepting when the bar 21 is swung downwardly to vertical position by the suspension therefrom of the bucket 7, an insulator or barrier 32 is normally disposed between said contacts, and is carried by a bracket 33 which is mounted on a rod 34 disposed slidably above the beam 18, said bracket being clamped between a pair of adjusting nuts 35 threaded on said rod. The rod 34 is connected to a slide 36 which moves on the beam 18 and which has a roller 37 or other means for the contact of the bar or bridle 21, so that the rod 34 is pushed rearwardly when the bar 21 is swung from the full line to the broken line position as seen in Fig. 1. A coiled compression spring 38 is confined between the post 17 and an adjusting nut 39 on the rod 34, to move said rod forwardly, thereby moving the insulator 32 between the contacts 23 and 24, and also swinging the bar 21 to the inclined position shown in full lines in Fig. 1. A stop nut 40 is

threaded on the rod to contact with the post 17 and thereby limit the forward movement of said rod.

With the parts in position as shown in Fig. 5 1, the lever 16 may be depressed, but the insulator 32 will prevent the contact 24 from touching the contact 23, so that the circuit 15 remains open. This will prevent the operation of the register, should the operator or 10 attendant make effort to operate the register falsely. It is also necessary that the lever 16 be depressed with sufficient force to overcome the spring 20, which is a further check against false operation of the register.

15 When the bucket 7 is suspended from the bar 21, said bar will be swung to vertical position, thereby pushing the rod 34 rearwardly, and the insulator 32 will be withdrawn from between the contacts 23 and 24, so that 20 the depression of the lever 16 will move the contact 24 against the contact 23, thereby closing the circuit 15. When the weight of the bucket 7 is released from the bar 21, the spring 38 restores the insulator 32 and bar 21 25 to normal position.

The register 13 includes the dial wheels 41, 42 and 43 for units, tens, and hundreds, and additional wheels may be employed, said 30 wheels being mounted for rotation in a case 44 which has openings or windows 45 through which the numerals on said wheels are exposed to indicate the number of operations of the register. As well known in registers, the wheel 42 is rotated one step for each complete revolution of the wheel 41, and the wheel 43 is rotated one step for each complete revolution of the wheel 42. As shown, this is accomplished by fingers 46 on the wheels 41 and 42 which contact with annular series of 35 pins 47 on the respective wheels 42 and 43. The wheels have ratchet teeth engaged by 40 pins 48 to prevent reverse rotation of said wheels.

A lever 49 is fulcrumed, as at 50, within the 45 case 44 and its movement is limited by adjustable stop screws 51, and said lever carries a pawl 52 to engage the ratchet teeth of the wheel 41, to move said wheel 41 one step for each oscillation of said lever. The lever 49 is connected with an armature 53 within the 50 influence of an electromagnet 54 connected in the circuit 15, so that when the circuit is closed and the electromagnet energized, the armature 53 is swung to depress the lever 49, to thereby advance the wheel 41 one step, and when the electromagnet is deenergized, 55 the lever 49 is restored by a spring 55.

In order to prevent the register from being 60 operated two or three times in rapid succession, such as might be attempted by the operator or attendant, means is provided whereby a time interval is necessary between the successive operations of the register. As shown, such means comprises a dash pot including 65 the cylinder 56 in the case 44 and a piston

57 connected to the lever 49 and working in said cylinder, said cylinder having a check-valved inlet 59, and a valve controlled vent 58. Thus, air may flow freely into the cylinder through the inlet 59 when the lever 49 is depressed, but the upward movement of the lever 49 is retarded by the slow discharge of the air through the valve 58, the inlet 59 having a check valve to prevent outflow through said inlet. The valve 58 may be adjusted so as to regulate the time required for the upward movement of the lever 49. The time interval may therefore be such as to prevent the repeated operation of the register excepting when sufficient time has elapsed for the repeated operation of the hoist. The dash pot will therefore not interfere with the normal operation of the register by the successive operations of the hoist, but will prevent the register from being operated more often than the 85 normal operations of the hoist.

Having thus described the invention, what is claimed as new is:—

1. The combination with a hoist bucket and hoisting means therefor, of means attachable to the lower portion of the bucket for suspending it in inverted position, a register, and controlling means for said register operated by said suspending means.

2. The combination with a hoist bucket and hoisting means therefor, of a yieldable member, means attachable to the lower portion of the bucket for suspending it in inverted position from said member, a register, and controlling means for said register operated by said member.

3. The combination of a lever, spring means for raising it, suspending means for a hoist bucket adjustably connected with said lever, a register, and controlling means for the register operated by said lever.

4. The combination with a hoist bucket and hoisting means therefor, of means attachable to the lower portion of the bucket for suspending it in inverted position, an electrically operated register, and a circuit controller for said register operated by said suspending means.

5. The combination with a hoist bucket and hoisting means therefor, of a yieldable member, means attachable to the lower portion of the bucket for suspending it in inverted position from said member, an electrically operated register, and a circuit controller for said register operated by said member.

6. The combination of means for suspending a hoist bucket in dumping position, a register, controlling means for the register operated by said suspending means, and means preventing the control of said register by said controlling means excepting when said suspending means is in suspending position.

7. The combination of means for suspend-

ing a hoist bucket in dumping position, an electrically operated register, a circuit controller for said register operated by said suspending means, and means preventing the control of said register by said controller excepting when said suspending means is in suspending position.

8. The combination of means for suspending a hoist bucket in dumping position, a register, controlling means for the register operated by said suspending means, and means normally preventing control of said register by said controlling means and arranged to be rendered inoperative when said suspending means is moved to suspending position.

9. The combination of a yieldable member, means for suspending a hoist bucket in dumping position from said member, a register, controlling means for the register operated by said member, and means normally preventing control of the register by said controlling means and arranged to be rendered inoperative when said suspending

means is moved to suspending position.

10. The combination of means for suspending a hoist bucket in dumping position,

a register, a circuit controller controlling said register, and operated by said suspending means, and means normally preventing control of the register by said controller and arranged to be rendered inoperative when said suspending means is moved to suspending position.

11. The combination of a yieldable member, means for suspending a hoist bucket in dumping position from said member, an electrically operated register, a circuit controller for said register operated by said member, means normally preventing control of said register by said controller, and means for rendering the last named means inoperative when the suspending means is moved to suspending position.

12. The combination of means for suspending a hoist bucket in dumping position and normally moved to another position, a register, and an operative connection between said register and means for operating the register by the depression of said means when in suspending position only.

In testimony whereof I hereunto affix my signature.

WILLIAM W. CROW.
